Primary Examiner—A. Hugo Word*Assistant Examiner*—Celia A. Murphy*Attorney, Agent, or Firm*—Henry R. Lerner[57] **CLAIM**

The ornamental design for an eyeglass case, as shown and described.

DESCRIPTION

FIG. 1 is a perspective view of an eyeglass case showing our new design;

FIG. 2 is a top plan view thereof;

FIG. 3 is a front elevational view thereof;

FIG. 4 is a right side elevational view thereof, the left side being a mirror image thereof;

FIG. 5 is a rear elevational view thereof;

FIG. 6 is a bottom plan view thereof; and,

FIG. 7 is a perspective view thereof being shown in an open position; the broken lines showing a pair of eyeglasses and spare temples being for illustrative purposes only and forming no part of the claimed design.
